United States Patent Office

Des. 193,817
Patented Oct. 9, 1962

193,817

HOUSEBOAT

Ormond L. Luger, 9612 Oakland Ave., and Rennold J. Luger, 4505 Belvidere Lane, both of Minneapolis, Minn.

Filed Dec. 22, 1960, Ser. No. 63,297

Term of patent 14 years

(Cl. D71—1)

FIG. 1

FIG. 2

FIG. 3

FIG. 4

FIG. 1 is a front perspective view of a houseboat showing our new design;

FIG. 2 is a rear perspective view thereof;

FIG. 3 is a front elevational view thereof; and

FIG. 4 is a rear elevational view thereof.

The bottom of the houseboat is conventionally plain.

We claim:

The ornamental design for a houseboat, as shown and described.
